CYRUS FISHER, OF CANTON, MASSACHUSETTS.

Letters Patent No. 66,232, dated July 2, 1867.

IMPROVEMENT IN MACHINE FOR SKEINING SILK, THREAD, &c.

The Schedule referred to in these Letters Patent and making part of the same.

TO ALL PERSONS TO WHOM THESE PRESENTS SHALL COME:

Be it known that I, CYRUS FISHER, of Canton, in the county of Norfolk, and State of Massachusetts, have invented a new and useful Machine for Skeining Silk or other Thread or Cord; and I do hereby declare the same to be fully described in the following specification, and represented in the accompanying drawings, of which—

Figure 1 is a top view, and

Figure 2 a front elevation of it.

In such drawings, A is the frame of the machine. To this frame are affixed two puppets or adjustable brackets, B B', which are to be so applied to the frame as to be movable therein horizontally, both toward and away from each other, each being fixed to the frame by a set-screw, a, going through a slot, b, in the bracket or puppet. Each bracket or puppet supports an arbor, C, which, at its lower end, terminates in a hook, D. There is a toothed pinion, e, to each arbor, it being made to engage with one of two driving-gears, d d', which are arranged on a horizontal shaft, e, one of them, d, being so applied thereto as to be capable of being adjusted or moved thereon lengthwise of it. A set-screw, e', in the hub of the gear, serves to fix the gear to the shaft, which should be provided with a groove arranged longitudinally in it, and to receive the end of the set-screw, so as to prevent the gear from revolving in the shaft. The shaft, also, should be capable of being moved lengthwise in its bearings. A crank, f, projecting from one of the gears d d', serves to enable a person to revolve the two gears simultaneously, so as to effect synchronous rotations of the two hooks of the arbors. Furthermore, there is between the two puppets B B' a rotary flyer, D², which, in form, is analogous to a crank. It projects from a tubular shaft, g', arranged over the shaft e, and at right angles therewith. The said shaft g' carries a bevel-gear, h, which engages with a bevel-pinion, i, fixed on the inner end of an inclined shaft, k, which is supported in bearings in a bracket, l, extends over the next adjacent gear, d', and is provided with a crank, m'. By revolving the crank the flyer will be caused to revolve in a circular path, going through the openings of the two hooks when the latter are horizontal, or in the positions as represented in the drawings. The flyer is composed of an arm, m, and a leg or piece of metal, n, arranged at right angles, or thereabouts, to each other, and so applied together as to enable the part n to be moved on the arm m, either nearer to or farther from the axis of the shaft g', from which the arm extends. A set-screw, o, going through a slot, p, in the part n, and being screwed into the arm, serves to fix the flyer leg to such arm. This adjustment of the flyer leg becomes essential in order to adapt the flyer to operate with the hooks, which are also adjustable, as described, for the purpose of arranging them for the production of skeins of different lengths. One of the hook arbors slides freely lengthwise in its bracket and pinion e, and is provided with a retraction spring, q, which is arranged between the pinion e of the arbor and a head or nut, r, screwed or fixed on the outer end of the arbor. The pinion is connected with the arbor by a feather connection; and there is a small projection, r², erected on the said bracket, for the thumb of a person to bear against while he, with his fore-finger, may be in the act of forcing the arbor inward. The object of such a movement of the arbor is to enable a skein, after its completion, to be readily detached from the two hooks. A cylindrical box or case, F, is placed on and fixed to one of the arbors of the hooks, so as to be concentric with such arbor. This box is in two parts or segments, s t, hinged together, and provided with a spring-catch, u, the same being as shown in fig. 3, which is a section of the box and the arbor, such section being taken in a plane at right angles to the arbor. The said box or case is to receive each of the skeins after being made, and without it being disconnected from the succeeding or preceding one.

In preparing the machine for winding a thread into a skein, the thread should be run through the shaft of the flyer and thence through guide-holes made in the leg of the flyer, from whence it should continue to one of the hooks, both of which should be arranged horizontally, so that while the flyer may be in revolution it may pass through their openings. On putting the flyer in revolution it will wind the thread upon the two hooks. After a sufficient quantity may have been wound upon them, the mass extending from hook to hook is to be wound in a helix by the thread, this being accomplished by putting the two hooks in revolution and guiding the thread along on the mass while it may be revolved. Each skein or "twist," as it is usually termed, after having been thus made, and without being separated from the thread of the flyer, may be removed from the hooks and placed in the box or case F, and another skein should next be made in a similar way. Fishing-lines, composed

of a series of connected skeins, are thus put up for sale in the market, and it is the purpose of the machine to so prepare them, as well as to reduce silk thread to what is termed a "twist." The box should have one or more notches, 2, made in the upper edge of the inner side of the larger segment, such notch being for reception of the thread proceeding from the skein in the box to that of the flyer or on the hooks.

I make no claim to the invention constituting the subject of Letters Patent of the United States numbered 12,668, and dated April 10, 1855.

I claim the combination and arrangement of the thumb-rest r^2 with the next adjacent rotary hook and its puppet.

I also claim the arrangement of the driving-shaft K of the flyer with respect to the flyer-shaft, and to the driving-gear of the next adjacent rotary hook.

I also claim the combination, as well as the arrangement, of the skein case F with the flyer, and the rotary hooks and mechanism for revolving them, as described.

CYRUS FISHER.
